UNITED STATES PATENT OFFICE.

FREDERICK H. COLLINS, OF SAN FRANCISCO, AND MARTIN L. PELLETT, OF BERKELEY,
CALIFORNIA.

INCINERATOR.

1,230,380.

Specification of Letters Patent. Patented June 19, 1917.

Application filed March 15, 1916. Serial No. 84,805.

10 *to all whom it may concern:*

Be it known that we, FREDERICK H. COLLINS, of the city and county of San Francisco, State of California, and MARTIN L. PELLETT, of Berkeley, county of Alameda, State of California, citizens of the United States, have invented new and useful Improvements in Incinerators, of which the following is a specification.

10 Our invention relates to a crematory or incinerating apparatus, which is especially designed for the purpose of disposing of garbage such as may be collected in cities and towns.

15 It consists in the disposition and arrangement of a furnace, a chamber through which the fire from the furnace passes, an arched roof above said chamber having a charging chute above, with doors so disposed that the chute may be filled above the closed gate in the arch of the cremating chamber, and a second closure at the upper end of the chute through which charges may be delivered into the chute from a hopper or receiver 20 above and the chute may be closed and the charge dried out before delivery into a fire chamber. A car is disposed to run upon rails beneath the discharge passage of the chute so as to receive the material to be destroyed; and this car has gates or shutters in the bottom through which the ashes may be discharged into an adjacent pit over which the car is designed to pass after the incineration is complete.

25 Our invention also comprises details of construction which will be more fully explained by reference to the accompanying drawings, in which—

30 Figure 1 is a horizontal section, taken on line 1—1 of Fig. 5, and a plan view of the ash pit.

Fig. 2 is an enlarged plan view of the car.

Fig. 3 is a section taken on the line 3—3 of Fig. 1.

35 Fig. 4 is a sectional view of the car, with its gates and the receiving ash pit.

Fig. 5 is a longitudinal section, taken on the line 5—5 of Figs. 1 and 3.

Fig. 6 shows the doors 14 open.

40 The structure, generally indicated at A, is an arched main chamber, having at one side thereof a combustion space and grate 2, upon which a hard fuel, such as coal, may be employed, or liquid fuel may be introduced by any well-known burner, not here

illustrated. From this furnace portion the products of combustion pass through the main chamber A under the arch, and upon the opposite and lower side of the chamber the fumes are delivered into flues 3 provided with controlling dampers, as at 4, so that the draft may be controlled. The products of combustion from the combustion chamber will reverberate through the arch 5 and the heat is therein concentrated and driven downward so as to impinge upon the contents of the car 6.

45 The car 6 is constructed with wheels 7 adapted to run upon rails in the pit below the level of the combustion space, and said car has a double dumping bottom composed of sections 8 through which the contents of the car may be discharged at the proper time. The rails, upon which the car travels, lead directly out through an opening in the 50 chamber adapted to be closed by a vertically movable door 9 and the car may travel on said rails to any point for convenient discharge of the ashes. Such a discharge point is indicated as a pit 10, over which the rails 55 pass so that the car may reach this point, and when it has reached this point the ashes may be delivered by opening the bottom of the car, which, as shown in Fig. 4, comprises two leaves hinged in such a manner that 60 when closed they support the contents of the car and when, by a turning lever or handle, as 11, these bottom leaves are released, they will turn into an edgewise position, as shown in Fig. 4, and allow the ashes to discharge. 65

70 In the upper part of the arch, and above the line of movement of the car, is a charging passage 12, and in line above this is a chamber or chute 13 of considerable length. The bottom of this chute is provided with 75 doors 14 which serve to close the passage, when desired. In the upper part of this chute are hinged swinging gates 15, so disposed that they may swing together and thus form a roof for the chute or passage. 80 These gates may be operated by means of a lever 16, connecting links 17 and levers 18, and when the material to be incinerated is brought to the furnace it may be discharged into a bin or hopper 19 which is located 85 above the gates 15 of the chute. These gates being opened an amount of material will pass into the drying chute from the receiving hopper until the chute is filled. The upper gates may then be closed and the 90

95

100

105

110

material in the drying chute will be subjected to the heat of the furnace chamber until as much of the moisture as desired has been expelled from the material to be cre-
5 mated.

The lower gate is then opened and the charge of the material in the drying chute may be delivered upon the car beneath. This gate is then closed and the carload of ma-
10 terial is subjected to sufficient heat to reduce it to ashes, after which the car may be run out and the charge delivered through the bottom and into the pit, as before de-
scribed.

15 As shown in Fig. 5, the doors 14 are connected by the bell crank levers 23, links 22 and 24 and lever 25 so that they operate in unison. The doors 14, forming the bottom of the drying chamber, are two in number and are slideable to and from each other in guides having anti-frictional bearings, as at 14^a. These doors are moved apart in opposite directions to open and are moved together to close. The doors have lugs 21
25 near their outer ends and these lugs are connected by links 22 with fulcrumed bell-crank levers 23, the shorter arms of which are connected by links 24 with a main operating lever 25 extending outside to a point 30 within convenient reach. When this lever is pulled up, it acts through the above connections to slide the doors apart and deliver the partially dried charge upon the car 6, for completion of the work.

35 The leaves 8 of the car bottom are hinged, as at 27, above and interiorly of the line of the car frame, and their meeting edges are supported, when closed, upon a longitudinally slideable member 28 by means of lugs 40 on the leaves and notches are provided in said member which are adapted to be brought into registration with the lugs to allow the leaves to swing open. This registration is accomplished by moving the member 28 longitudinally by means of a crank 45 lever 11.

Having thus described our invention, what we claim and desire to secure by Letters Patent is—

50 1. An incinerating apparatus, comprising a main chamber, a fireplace located in one side of said chamber, a car at the other side of said chamber, a drying chamber located above said main chamber at a point above
55 the position of the car when in said main

chamber, gates at the bottom of said drying chamber for controlling communication between said drying chamber and said main chamber, gates at the top of said drying chamber, the space between said top and bottom gates being adapted to measure the charge introduced into said main chamber upon the car therein, and a supply hopper above the drying chamber.

2. In a garbage crematory of the character disclosed, a chamber having a fuel combustion space interiorly located at one side, a track extending into the chamber at one side of said fuel combustion space and at a level below said combustion space, a car in 70 said chamber movable on said track, a drying chamber located above the car, means for controlling the charge in said drying chamber, and a plurality of draft flues connecting with the side of the chamber opposite 75 the combustion space.

3. In a garbage crematory of the character described, a chamber containing a fuel grate and a car parallel with each other and upon opposite sides of the chamber, an approximately vertical drying chute extending above the car having doors at each end, means for charging the chute, and means to open and close the doors to deliver garbage upon the car.

4. In a garbage furnace, a main chamber, a fuel combustion space communicating with said main chamber, a drying chute leading to said main chamber and adapted to receive heat from said combustion space, 90 doors for controlling communication between said drying chute and said main chamber, doors for closing the outer end of said drying chute, a car located in the furnace below said drying chute to receive the charge of material from said drying chute, said car being also located in such position with relation to said combustion space that the heated gases therefrom pass over the car and through the material thereon to complete the drying of the material.

In testimony whereof we have hereunto set our hands in the presence of two subscribing witnesses:

FREDERICK H. COLLINS.
MARTIN L. PELLETT.

Witnesses:

GEO. H. STRONG,
JOHN H. HERRING.
